(57) **CLAIM**

The ornamental design for a display screen or portion thereof with a graphical user interface, as shown and described.

DESCRIPTION

FIG. 1 is a front view of the display screen or portion thereof with icon, according to a first embodiment; and

FIG. 2 is a front view of a second embodiment thereof; and,

FIG. 3 is a front view of a third embodiment thereof.

The two outer broken lines illustrate a display screen and form no part of the claimed design. The remaining broken lines illustrate portions of the graphical user interface and form no part of the claimed design.

1 Claim, 3 Drawing Sheets
